UNITED STATES PATENT OFFICE.

WILLIAM G. KENDALL, OF NEWARK, NEW JERSEY.

SAFETY-CATCH.

1,228,025.

Specification of Letters Patent. Patented May 29, 1917.

Application filed February 27, 1917. Serial No. 151,299.

To all whom it may concern:

Be it known that I, WILLIAM G. KENDALL, a citizen of the United States, residing at Newark, in the county of Essex and State 5 of New Jersey, have invented certain new and useful Improvements in Safety-Catches, of which the following is a specification.

My invention relates to new and useful improvements in safety catches for pins, 10 and more particularly for pins of the so-called safety-pin type, the primary object of my invention being the provision of a catch which will be relatively small, economical to manufacture, applicable to pins 15 already in use and efficient in its action.

A still further object which I have in view is the construction of a catch embodying a pair of keeper hooks the terminals of 20 which turn downwardly to tend to retain a pin engaged in them, a swinging locking plate adapted to fit snugly between the hooks and curved intermediate its length to correspond to the curvature of the hooks, and a locking stud or projection carried by 25 the locking plate and adapted to project from it to the base of the catch to provide an absolute barrier against disengagement of the pin from the hooks when the catch is in place.

Another object which I aim to accomplish 30 is the provision of means for effectively holding the locking plate in active position when once applied.

With these and other objects in view, my 35 invention will be more fully described, illustrated in the accompanying drawings, and then specifically pointed out in the claims which are attached to and form a part of this application.

In the drawings:

Figure 1 is a rear elevation of a conventional form of bar pin showing my catch in use;

Fig. 2 is a side elevation of the catch;

Fig. 3 is a longitudinal sectional view of 45 the catch taken on the line 3-3 of Fig. 1 but not showing the pin;

Fig. 4 is a perspective view of the catch in open position;

Fig. 5 is a side elevation of a somewhat 50 modified form of catch in closed position;

Fig. 6 is a central longitudinal sectional view of the catch shown in Fig. 5; and

Fig. 7 is a perspective view of the catch 55 shown in Fig. 5 in open position.

Corresponding and like parts are referred

to in the following description and indicated in all the views of the accompanying drawings by the same reference characters.

In order to insure a clear and accurate 60 understanding of my improved catch construction and its operation, I have illustrated it in connection with a conventional form of bar pin including the body 10 provided upon its rear face and adjacent one 65 end with spaced ears 12 to pivotally receive the unpointed end of the pin proper 13. My catch, indicated as a whole by the numeral 14, is shown in Fig. 1 as lockingly receiving the pin proper adjacent its pointed end, the catch for obvious reasons being disposed transversely of the body 10 of the bar pin.

For an understanding of the details of 70 structure of the catch itself, reference 75 should be had to Figs. 2 to 4 inclusive, of the drawings. As there shown the catch includes a base portion 15 which is preferably of sheet metal and rectangular in shape and which is provided at its sides with 80 upstanding projections or walls 16, these walls being preferably stamped out as a single piece with the base and then bent into vertical parallel relation as shown. The upper edges of these walls are cut away to provide 85 at one end a pair of ears 17 projecting a considerable distance from the base 15 and at their opposite ends a pair of keeper hooks 18. The shank portions of these hooks project vertically with respect to the base and 90 the bill portions are curved toward the ears 17 and then downwardly so as to provide with the upper edges of the remaining portions of the side walls a relatively narrow or 95 restricted pin-receiving passage 19. The outer faces of the hooks are curved to correspond with the inner faces in order that the 100 pin may ride readily over them to the passage 19 and then be swung through this passage and rearwardly away from the body of the pin to seat in the bight portions of 105 the hooks. Obviously these hooks will hold the pin against any movement other than movement through the passage 19 between the terminals and the walls 16.

A substantially rectangular locking plate 20 of sheet metal is provided in slightly spaced relation to one end with laterally directed trunnions 21 which pivotally seat in 110 perforations 22 formed in the ears 17 and in alignment with each other. This plate is provided intermediate its length with an

outcurved portion 23 and its free terminal is bent at an angle to the body of the plate so that when the plate is swung to active position as shown in Figs. 2 and 3 the body 5 of the plate will be parallel to the base, the curved portion will be concentric with and disposed between the hooks and its terminal will engage against the end of the base. This terminal is slightly upbent as shown 10 at 24 so that it may be readily engaged by the finger of the wearer of the pin to facilitate its movement to inactive position. A leaf spring 25 is secured, by a rivet 26 or other suitable means, to the base 15 between 15 the hook portions of the side walls and has its free end outsprung to constantly engage against the pivotal terminal of the locking plate 20 so as to yieldably hold the plate in either active or inactive position and to offer 20 resistance to the stopping of the plate in any intermediate position, the terminal of the plate wiping back and forth across the spring during movement of the plate from one position to the other.

25 A locking stud or pin 26^a has one end fixed in the plate at the juncture of the body portion of the plate and its outcurved portion in such a manner as to extend downwardly when the plate is in active position 30 and at a slight angle toward the shank portions of the hooks. This pin when the plate is in active position engages against the spring 25 so as to completely close the passages 19 and because of its inclination any 35 movement of the pin proper toward the passage will bring it into engagement with the inclined locking stud 26^a in such a manner that further movement of the pin proper will not only be prevented but strain tending 40 to move it farther will act against the stud in a direction to more closely press the locking plate into active position. The pin proper may, however, be freed from the catch at any time by holding it in the bight 45 portion of the hooks and manually swinging the plate against the action of its spring into inactive position when the pin may be removed from the hooks in the usual manner.

In Figs. 5 to 7, inclusive, I have illustrated 50 a modified form of safety catch which in most respects is identical with the form previously described. In this modified form of hook construction the base does not project beyond the ears 17 as in the form first 55 described and the opposite end of the base terminates substantially in alignment with the bight portions of the hooks. Furthermore the locking plate has its free terminal bent downwardly and inwardly as shown at 60 27 so that in active position it abuts against the adjacent edge of the base instead of against the upper face of the base. Preferably for the sake of convenience the outer faces of the shank portions of the hooks 65 conform in curvature to the curvature of

this terminal 27. The outcurved intermediate portion of the locking plate is provided with a radially extending finger piece or stud 28 in order that the plate may be readily swung to open or to active position and the side walls of the body of the catch are so spaced that there is a slight wedging action between them and the base of the locking plate when it is swung to active position which will serve to hold it against any possible movement due to gravity such as might occur during shaking of the garment upon which a pin equipped with the catch was fastened. The modified form of catch is otherwise identical with that previously 75 described and for this reason the corresponding parts have been given similar reference characters.

Obviously the base portions of the catches described may be omitted and the side wall 80 portions may be as separate elements and soldered or otherwise secured directly to the rear face of the body of the pin if desired. This structure will not, however, be as rigid 85 as that shown and would require more delicate workmanship in its application. However, I do not wish to limit myself to the specific details of construction and particular arrangement of parts shown, but reserve the right to make any changes, within the 90 scope of the appended claims, without in the slightest degree departing from the spirit 95 of my invention.

Having thus described my invention, what I claim as new and desire to secure by Let- 100 ters Patent is:

1. A safety clasp applicable to pins of the safety-pin type including a base adapted to be secured to the rear face of the pin, outstanding side walls projecting in substantially parallel spaced relation from the base, the walls being cut away to define ears at one end and rebent hook portions at the other end the bills of which are curved toward the ears and base to provide restricted 105 pin point receiving passages, and a locking plate pivoted adjacent one end between the ears and engaging at its other end against the base when in active position, the intermediate portion of the locking plate being 110 outcurved to conform to the curvature of the hooks and to fit snugly between them. 115

2. A safety clasp applicable to pins of the safety-pin type including a base adapted to be secured to the rear face of the pin, spaced outstanding side walls projecting from the base, the walls being cut away to define ears at one end and rebent hook portions at the other end the bills of which are curved toward the ears and base to provide restricted 120 pin point receiving passages, a locking plate pivoted adjacent one end between the ears and engaging at its other end against the base when in active position, the intermediate portion of the locking plate being 125 out- 130

curved to conform to the curvature of the hooks and to fit snugly between them, and a locking stud fixed to the intermediate portion of the locking plate and projecting 5 downwardly across the passages when the plate is in active position.

3. A safety clasp applicable to pins of the safety-pin type including a base adapted to be secured to the rear face of the pin, spaced 10 outstanding side walls projecting from the base, the walls being cut away to define ears at one end and rebent hook portions at the other end the bills of which are curved toward the ears and base to provide restricted 15 pin point receiving passages, a locking plate pivoted adjacent one end between the ears and engaging at its other end against the base when in active position, the intermediate portion of the locking plate being out- 20 curved to conform to the curvature of the hooks and to fit snugly between them, and a locking stud fixed to the intermediate portion of the locking plate and projecting downwardly across the passages with its 25 free end with slight inclination toward the free end of the locking plate when the plate is in active position.

4. A safety clasp applicable to pins of the safety-pin type including a base adapted 30 to be secured to the rear face of the pin, spaced outstanding side walls projecting from the base, the walls being cut away to define ears at one end and rebent hook portions at the other end the bills of which 35 are curved toward the ears and base to provide restricted pin point receiving passages, a locking plate pivoted adjacent one end between the ears with its other end adapted to

engage the base when the plate is in active position, the locking plate being outstruck 40 intermediate its length to conform in curvature to the curvature of the hooks and to lie between them, and a leaf spring fixed to the base at one end between the hooks with its other end in engagement with the 45 pivoted end of the plate so that such end of the plate will wipe over the spring during swinging and be held in either active or inactive position.

5. A safety clasp applicable to pins of the 50 safety-pin type including a base adapted to be secured to the rear face of the pin, outstanding side walls projecting in parallel spaced relation from the base, the upper edges of the walls being cut away to define 55 ears at one end and rebent hook portions at the other end the bills of which are curved toward the ears and base to provide restricted pin point receiving passages, a locking plate pivoted adjacent one end between 60 the ears and engaging at its other end against the base when in active position, the locking plate being outstruck intermediate 65 its length to conform in curvature to the curvature of the hooks and to lie between 70 them, a leaf spring fixed to the base at one end between the hooks with its other end in engagement with the pivoted end of the plate so that such end of the plate will wipe over the spring during swinging and be held 75 in either active or inactive position, and a locking stud projecting from the plate to extend across the passages and engage the spring when the plate is in active position.

In testimony whereof I affix my signature. 75
